(57) **CLAIM**

The ornamental design for a pair of shoes, substantially as shown and described.

DESCRIPTION

FIG. 1 is a front perspective view of a shoe, showing one implementation of our design;

FIG. 2 is a front view of the shoe of FIG. 1;

FIG. 3 is a rear view of the shoe of FIG. 1;

FIG. 4 is a left side view of the shoe of FIG. 1;

FIG. 5 is a right side view of the shoe of FIG. 1;

FIG. 6 is a top view of the shoe of FIG. 1;

FIG. 7 is a bottom view of the shoe of FIG. 1, showing a sole surface tread design;

FIG. 8 is a rear perspective view of the shoe of FIG. 1;

FIG. 9 is a front perspective view of a shoe, showing another implementation of our design;

FIG. 10 is a front view of the shoe of FIG. 9;

FIG. 11 is a rear view of the shoe of FIG. 9;

FIG. 12 is a left side view of the shoe of FIG. 9;

FIG. 13 is a right side view of the shoe of FIG. 9;

FIG. 14 is a top view of the shoe of FIG. 9;

FIG. 15 is a bottom view of the shoe of FIG. 9, showing a sole surface tread design;

FIG. 16 is a rear perspective view of the shoe of FIG. 9;

FIG. 17 is a front perspective view thereof;

FIG. 18 is a front view of the shoe of FIG. 17;

FIG. 19 is a rear view of the shoe of FIG. 17;

FIG. 20 is a left side view of the shoe of FIG. 17;

FIG. 21 is a right side view of the shoe of FIG. 17;

FIG. 22 is a top view of the shoe of FIG. 17;

FIG. 23 is a bottom view of the shoe of FIG. 17, showing a sole surface tread design; and,

FIG. 24 is a rear perspective view of the shoe of FIG. 17.

The drawings show the design of a shoe suitable for being worn on a wearer's right foot. The ornamental design also includes the mirror images of drawings, i.e., the design of a shoe suitable for being worn on a wearer's left foot.

1 Claim, 21 Drawing Sheets
